UNITED STATES PATENT OFFICE

1,990,572

GARMENT

Samuel F. Stein, Williamsport, Pa.

Application February 26, 1932, Serial No. 595,414

1 Claim. (Cl. 2—236)

My invention relates to a new and useful improvement in the art of making garments and more particularly it has to do with the waistband construction of trousers or knickerbockers having a waistband lining known as a waistband curtain and it concerns the attaching of buttons to such a curtain. By my invention a finished product is secured that is entirely satisfactory as far as the attaching of suspender buttons to the trouser curtain is concerned, and a saving in manufacturing cost is effected.

My invention consists in whatever is described by or is included in the terms or scope of the appended claim.

15 In the drawing:

Fig. 1 is a side view showing the waist portion of trousers, turned inside out, the waistband curtain of which is constructed in accordance with my invention.

20 Fig. 2 is a section in line 2—2 of Fig. 1.

Referring to Fig. 1, of the drawing, 10, illustrates the upper portion of a pair of trousers turned inside out; 11, represents the trouser curtain which extends around the waist of the trousers; 12, represents the front suspender buttons; 13, the back suspender buttons; 14, the front suspender straps, and 15, the back suspender straps. This view shows as much of the waistband curtain as goes around half way the waist of the trousers, the construction of the other half of the curtain of the trousers is the same as the part illustrated.

In the ordinary construction of a trouser curtain, stiffening material and lining cloth are used to make up the body of the curtain and buttons are attached to the curtain by stitches which pass through the curtain body. There are front and back suspender buttons, and when the front suspender straps pull on the front suspender buttons and the back suspender straps pull on the back suspender buttons there is a tendency for the stiffening material to tear at a point intermediate the front and back suspender buttons. Inasmuch as the lining cloth is comparatively thin and the stiffening material comprises a starched body, the latter is apt to force itself through the lining cloth of the curtain while the buttons are still attached to the stiffened material and the latter being torn intermediate the front and back buttons, with the result that the buttons become loose and pulled away from the curtain of the trousers.

My invention provides a line of cord or tape 16, (shown in dotted lines) which is attached to the curtain longitudinally by means of stitching or

other attaching means. The buttons are attached to the curtain directly on this line by sewing or otherwise and any strain or pull on the buttons 12, or buttons 13, will not cause the buttons to spread apart, as the case would be in the ordinary construction, for the reason that the cord or tape 16, is sufficiently strong to hold the buttons in place and also to prevent the stiffening material from tearing at any point between the buttons. Aside from the advantage derived from my construction that the cord or tape 16, hinders the buttons from spreading away from one another it has the advantage also that the pull or strain on one of the front buttons 12, or on one of the back buttons 13, will be counteracted by the strain or pull on the other button of the front buttons 12, or on the other button of the back buttons 13.

The line of cord, or tape 16, when attached to curtain 11, either by stitching or otherwise, forms a straight line visible on the face of the curtain 11, which enables the button attaching operator to attach the buttons to the curtain directly on the line, which is very essential in the practice of my invention, and because the cord or tape line is rendered visible a comparatively narrow cord or tape may be utilized for this purpose. This tape line has another advantage in forming a guide for uniformly spacing all buttons a certain distance from the top.

The cord or tape 16, may be applied to the curtain by placing it on one side of the stiffening material and stitching through the tape, stiffening and lining, it may be either the inside or outside of the stiffening material. When the cord or tape 16, is attached to the inside of the stiffening, which is between the lining and stiffening, the cord or tape may be securely held in place by means of pasting, as the lining and stiffening often get pasted together to make up the body of the curtain, and the cord or tape 16 could conveniently be fed to be included in this operation. When the curtain is made of a single piece of material and when it is composed of only one thickness, the cord or tape 16 may be applied as well with all the advantages derived from my construction.

In the practice of my invention it is feasible that the buttons be attached to the curtains before the curtains are sewed to the trousers, in which case the handling of the work is greatly facilitated and the cost of attaching the buttons will thus be reduced considerably, as the operator need not handle the whole garment for the button attaching operation, besides saving considerable space at the button attaching machine.

When the cord or tape 16, extends longitudinally along the curtain it forms a raised line which will facilitate the hand sewing of buttons after the curtain has already been attached to the trousers, as it is found difficult to sew buttons on to the curtain with a blind stitch, or a stitch invisible on the outside of the trousers, when the curtain is absolutely flat and has no raised line. This cord or tape line 16 may also be used to advantage when it is desired to sew buttons on to the curtain by machine after the curtain has been attached to the trousers. This line being present in the curtain facilitates the folding of the curtain at that place, and when it is so folded, the folded edge may be put under a button held by a clamp of a button sewing machine, in such a way that the folded edge does not extend farther than two holes of the four-hole button, and by operating a button sewing machine with the stitching to and from the operator, the button may be sewed on to the curtain with stitches which are invisible on the outer side of the trousers. After the button is sewed on to the curtain in this manner, the curtain is smoothened out and the button lies smoothly on the line of the cord or tape. As shown in the drawing, stitches 18, may be placed over the cord or tape, 16, through the curtain 11, and trousers cloth, 10. By suitable guides the cord or tape 16, may be fed automatically and be attached to the curtain when the curtain is made in continuous rolls.

The cord or tape 16, may be of any desired flexible material suitable for the purpose.

It will now be apparent that I have devised a

novel and useful construction which embodies the features of advantage described herein and while I have in the present instance shown and described the preferred embodiment of my invention it is to be understood that the same is susceptible of modification in various particulars without departing from the spirit or scope of the invention or sacrificing any of its advantages.

Having thus described my invention, what I claim is:

As a new article of manufacture, a waistband curtain for trousers comprising a strip of facing material and a strip of stiffening material secured together in juxtaposed relation, said waistband curtain being subject to tear when the trousers are supported on the wearer by means of buttons and suspenders and when the suspender straps pull on said buttons, said waistband curtain having a strip comprising sufficient strength to hold the buttons that are attached thereto and being substantially narrower than the width of said buttons, said strip extending longitudinally along said waistband curtain in parallel relation to the longitudinal edge of the latter and spaced therefrom and secured thereto substantially below the top edge thereof, thus serving as a guide for attaching said buttons to said waistband curtain at points properly placed in relation with the top edge of the trousers, and providing a degree of resistance at the place of attachment to prevent the separation of said buttons from said waistband curtain and the tearing of the curtain material between the several buttons.

SAMUEL F. STEIN.
